UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed June 18, 1925. Serial No. 37,992.

My invention relates generally to internal combustion engines and more particularly to a multi-cylinder V-block engine that operates on the two stroke cycle principle and my invention has for its principal object the provision of a relatively simple and practical arrangement of transfer ducts for conveying charge volumes of gaseous fuel or the like from the pumping chambers in one wing of the V-block to certain of the combustion chambers in the opposite wing of said block.

My improved transfer duct arrangement is particularly designed for an engine having eight cylinders and which latter are arranged in two rows of four cylinders each with two of the cylinders of each row having straight diameter bores and the other two cylinders of said row having two diameters in order to provide a combustion chamber and a pumping chamber in each of said two-diameter bore cylinders.

My invention resides in the combination of transfer ducts between the pumping chambers or one row of cylinders with certain of the combustion chambers of the other row of cylinders, said two rows of cylinders being disposed parallel with the axis of the crank shaft, and said two rows of cylinders being arranged 90° apart with a two crank pin crank shaft and the pistons of the two end cylinders at either end of the two rows being connected to one of the two crank pins of said crank shaft thereby providing an arrangement whereby four pistons are connected to each crank pin and with two of the set of four pistons being angularly disposed with respect to the other two of said set of four pistons so that a proper time relation will exist for proper functioning of the transfer of the pumped fresh charge volume from the pumping chamber of one cylinder to a combustion chamber in the opposite row at a time when the respective action and position of the pistons within the combined pumping and combustion cylinders are such as to permit ejection and induction of the charge volume from one chamber to the other.

With the foregoing and other objects in view, my invention consists in certain novel features of construction and arrangement of

parts that will hereinafter be more fully described and claimed and illustrated in the accompanying drawings in which

Fig. 1 is a top plan view of an internal combustion engine having the improved arrangement of transfer ducts as contemplated by my invention.

Fig. 2 is a vertical longitudinal section taken on the line 2-2 of Fig. 1.

Fig. 3 is a diagrammatic cross section taken approximately on the line 3-3 of Fig. 1.

Fig. 4 is a diagrammatic cross section taken approximately on the line 4-4 of Fig. 1.

Fig. 5 is a diagrammatic cross section taken approximately on the line 5-5 of Fig. 1.

Fig. 6 is a diagrammatic cross section taken approximately on the line 6-6 of Fig. 1.

Referring by numerals to the accompanying drawing which illustrates a practical embodiment of my invention, 10 and 11 designate the wings of a substantially V-shaped cylindrical block, said wings being disposed in planes 90° apart, and said wings rising from a suitable crank case 12 and the latter being provided with three main bearings 13 for a crank shaft 14. This crank shaft has two crank pins 15 and 16 and each pin has two machined bearing surfaces that are adapted to be engaged by the lower ends of connecting rods as will hereinafter be more fully set forth. The crank pins of crank 14 are arranged directly opposite to each other or 180° apart.

Formed in block 10 adjacent to its ends are straight diameter bore combustion chambers 18 and 19 and formed in said block between said combustion chambers are two two-diameter bores, the upper portions of smaller diameter functioning as combustion chambers 20 and 21 and the lower portions of larger diameter functioning as charge volume pumping chambers 22 and 23.

The axes of the four chambers in wing 10 are parallel and in the same longitudinal plane, and said four axes intersect the axis of crank shaft 14. Secured on top of block 10 is a head block 24 having in its under-

side shallow recesses 25 and 26. Recess 25 connects and constitutes a common clearance space for the head or inner ends of combustion chambers 18 and 20 and in like manner recess 26 connects and constitutes a common clearance chamber for the head or inner ends of combustion chambers 19 and 21.

The structure and equipment of wing or block 11 is identical with that of block 10, 10 said block 11 having combustion chambers 27 and 28 adjacent to its ends and in transverse alignment respectively with combustion chambers 18 and 19. Formed in block 11 between the combustion chambers 27 and 15 28 are two two-diameter bores the upper or smaller portions 29 and 30 of which function as combustion chambers and the lower portions of larger diameter 31 and 32 function as charge volume pumping chambers. 20 The two-diameter chamber 29, 31, is disposed transversely opposite to the two-diameter chamber 20, 22, while the two-diameter chamber 30, 32 is in transverse alignment with the two-diameter chamber 21, 23. The 25 axes of the four bores or chambers in wing 11 are parallel and in the same longitudinal plane and their axes intersect the axis of crank shaft 14.

A head block 33 is arranged on the upper 30 end of wing 11 and formed in its underside are shallow recesses 34 and 35 which connect respectively the head ends of combustion chambers 27 and 29 and 28 and 30.

Straight diameter pistons such as 36 are 35 arranged for reciprocatory movement within the combustion chambers 18 and 27 and two-diameter pistons such as 37 are arranged for operation within the two-diameter chambers 20, 22 and 29, 31. The pair of straight diameter pistons 36 and the pair of two-diameter pistons 37 are connected by suitable connecting rods such as 38 to crank pin 15.

Straight diameter pistons such as 39 are arranged for operation within the combustion chambers 19 and 28 and two-diameter pistons 40 are arranged for operation within the two-diameter chambers 21, 23 and 30, 32. The two straight diameter pistons 39 and the two two-diameter pistons 40 are connected to crank pin 16 by connecting rods such as 41.

A charge volume transfer duct 42 leads from outlet ports at the upper end of pumping chambers 22 to inlet ports in the lower portion of combustion chamber 29 and a similar transfer duct 43 leads from outlet ports at the upper end of pumping chamber 23 to inlet ports that lead into the lower portion of combustion chamber 30. A charge 55 volume transfer duct 44 leads from outlet ports at the upper end of pumping chamber 32 to inlet ports that lead into the lower portion of combustion chamber 20. A fourth charge volume transfer duct 45 leads from 60 the outlet ports at the upper portion of

70 pumping chamber 31 to inlet ports that lead into the lower portion of combustion chamber 21. Obviously the charge volume pumping chambers 22, 23 and 31 and 32 must necessarily be provided with charge volume inlet ports, the same being located so as to admit gaseous fuel or the like into said pumping chambers when the pistons therein are at the lower ends of their travel and the combustion chambers 18 and 19 and 27 and 28 must be provided with exhaust ports such as 46 that are uncovered and open while the pistons that operate within said combustion chambers are at the lower ends of their travel.

80 As a result of my improved arrangement of transfer ducts between the wings of a V-block structure two stroke cycle internal combustion engine the charge volumes are pumped from the pumping chambers in one wing of the block to the smaller diameter or combustion chamber portions of the two-diameter chambers in the opposite block, and this transfer of the charge volumes is permitted to take place or be effected as a result of the V-arrangement of the two rows 85 or cylinders. The discharge of the two pairs of two-diameter cylinders and the arrangement whereby the four pistons at one end of the engine are connected to one pin of the two throw crank shaft and the pistons within the other four cylinders being connected to the other crank pin of said two throw 90 crank shaft.

95 Obviously minor changes in the size, form and construction of the various parts of my improved internal combustion engine may be made and substituted for those herein shown and described without departing from the spirit of my invention, the scope of 100 which is set forth in the appended claims.

105 I claim as my invention:

110 1. In a two stroke cycle internal combustion engine, two rows of cylinders arranged to form a V-structure with four cylinders in each wing of said V-structure and the wings being arranged 90° apart, the bores of the two center cylinders of each row having two diameters so that each of said two center cylinders has a combustion chamber and a pumping chamber, the two end cylinders of each row having straight diameter bores and a charge volume transfer duct leading from the upper portion of the pumping chamber of each two-diameter cylinder to the combustion chamber in one of the two-diameter cylinders in the opposite row.

115 2. In a two stroke cycle internal combustion engine, two rows of cylinders arranged to form a V-structure with four cylinders in each wing of said V-structure and the wings being arranged 90° apart, the bores of the two center cylinders of each row having two diameters so that each of said two center cylinders has a combustion chamber and a 120 pumping chamber, the two end cylinders of each row having straight diameter bores and a charge volume transfer duct leading from the upper portion of the pumping chamber of each two-diameter cylinder to the combustion chamber in one of the two-diameter cylinders in the opposite row.

- pumping chamber, the two end cylinders of each row having straight diameter bores, a charge volume transfer duct leading from the upper portion of the pumping chamber of each two-diameter cylinder to the combustion chamber in one of the two-diameter cylinders in the opposite row, a crank shaft having two crank pins arranged 180° apart, pistons arranged for operation within the four of the cylinders at one end of the V-structure being connected to one of the crank pins of said crank shaft and the pistons within the four cylinders at the other end of the V-structure being connected to the other one of the two pins of said crank shaft. 55
5. In a two stroke cycle internal combustion engine, two rows of cylinders arranged to form a V-structure with four cylinders in each wing of said V-structure, said wings being arranged 90° apart, the bores of the two cylinders of each row each having two diameters so that each of said two center cylinders has a combustion chamber and a pumping chamber, substantially straight transfer ducts leading from the pumping chambers in the left hand row of cylinders from the front end of the engine to the combustion chambers in the two center cylinders of the right hand row and crossed transfer ducts leading from the pumping chambers in the two center cylinders in the right hand row to the combustion chambers of the two center cylinders in said left hand row. 65
6. In a two stroke cycle internal combustion engine, two rows of cylinders arranged to form a V-structure with four cylinders in each wing of said V-structure, said wings being arranged 90° apart, the bores of the two cylinders of each row having two diameters so that each of said two center cylinders has a combustion chamber and a pumping chamber, substantially straight transfer ducts leading from the pumping chambers in the left hand row of cylinders from the front end of the engine to the combustion chambers in the two center cylinders of the right hand row, crossed transfer ducts leading from the pumping chambers in the two center cylinders in the right hand row to the combustion chambers of the two center cylinders in said left hand row and the two end cylinders of both rows having straight diameter bore chambers. 75
7. In a two stroke cycle internal combustion engine, eight cylinders arranged in two rows of four cylinders each, the two rows being disposed 90° apart, the two end cylinders of each row having straight diameter chambers, the two center cylinders of each row having two-diameter chambers, the smaller diameter portion of each two-diameter chamber constituting a combustion chamber the head end of which is connected by a common clearance space with the head end of the adjacent straight diameter chamber, the larger diameter portion of each two-diameter chamber constituting a pumping chamber and a transfer duct connecting each pumping chamber with a smaller diameter chamber of one of the two-diameter chambers in the opposite row of cylinders. 80
8. In a two stroke cycle internal combustion engine, eight cylinders arranged in two rows of four cylinders each, the two rows being disposed 90° apart, the two end cylinders of each row having straight diameter chambers, the two center cylinders of each row having two-diameter chambers, the smaller diameter portion of each two-diameter chamber constituting a combustion chamber the head end of which is connected by a common clearance space with the head end of the adjacent straight diameter chamber, the larger diameter portion of each two-diameter chamber constituting a pumping chamber, a transfer duct connecting each pumping chamber with a smaller diameter chamber of one of the two-diameter chambers in the opposite row of cylinders, a crank 85
9. In a two stroke cycle internal combustion engine, eight cylinders arranged in two rows of four cylinders each, the two rows being disposed 90° apart, the two end cylinders of each row having straight diameter chambers, the two center cylinders of each row having two-diameter chambers, the smaller diameter portion of each two-diameter chamber constituting a combustion chamber the head end of which is connected by a common clearance space with the head end of the adjacent straight diameter chamber, the larger diameter portion of each two-diameter chamber constituting a pumping chamber, a transfer duct connecting each pumping chamber with a smaller diameter chamber of one of the two-diameter chambers in the opposite row of cylinders, a crank 90
10. In a two stroke cycle internal combustion engine, eight cylinders arranged in two rows of four cylinders each, the two rows being disposed 90° apart, the two end cylinders of each row having straight diameter chambers, the two center cylinders of each row having two-diameter chambers, the smaller diameter portion of each two-diameter chamber constituting a combustion chamber the head end of which is connected by a common clearance space with the head end of the adjacent straight diameter chamber, the larger diameter portion of each two-diameter chamber constituting a pumping chamber, a transfer duct connecting each pumping chamber with a smaller diameter chamber of one of the two-diameter chambers in the opposite row of cylinders, a crank 95

In testimony whereof I affix my signature.
EVERETT R. BURTNELL.
